DESIGN FOR A COMB OR SIMILAR ARTICLE

Lester Kahn, Upper Montclair, N. J., assignor to E. I. du Pont de Nemours & Company, Wilmington, Del., a corporation of Delaware

Application October 5, 1938, Serial No. 80,266

Term of patent 7 years

To all whom it may concern:

Be it known that I, Lester Kahn, a citizen of the United States and a resident of Upper Montclair, in the county of Essex and State of New Jersey, have invented a certain new, original, and ornamental Design for a Comb or Similar Article, of which the following is a specification, reference being had to the accompanying drawing, forming part thereof.

In the accompanying drawing:

Figure 1 is a front elevational view of a comb or similar article embodying the design, showing the handle in an extended position.

The characteristic features of my design reside in the comb disclosed having the specific contour in cross-section best shown in Figure 4.

I claim:

The ornamental design for a comb or similar article, substantially as shown and described.

LESTER KAHN.
